Primary Examiner — Mitchell Siegel(74) *Attorney, Agent, or Firm* — Temmerman Law Office;
Matthew J. Temmerman(57) **CLAIM**

I claim the ornamental design for a golf ball target for chipping and putting, as shown and described.

DESCRIPTION

FIG. 1 is a perspective view of a golf ball target for chipping and putting showing my new design;

FIG. 2 is a top plan view thereof;

FIG. 3 is another perspective view thereof;

FIG. 4 is an enlarged fragmented top plan view thereof;

FIG. 5 is a perspective view of a second embodiment of a golf ball target for chipping and putting showing my new design;

FIG. 6 is a top plan view of FIG. 5;

FIG. 7 is another perspective view of FIG. 5;

FIG. 8 is an enlarged fragmented top plan view of FIG. 5;

FIG. 9 is a perspective view of a third embodiment of a golf ball target for chipping and putting showing my new design;

FIG. 10 is a top plan view of FIG. 9;

FIG. 11 is another perspective view of FIG. 9; and,

FIG. 12 is an enlarged fragmented top plan view of FIG. 9.
